UNITED STATES PATENT OFFICE.

ARTHUR M. HOUSER, OF CHICAGO, ILLINOIS, ASSIGNOR TO CRANE COMPANY, OF CHICAGO, ILLINOIS, A CORPORATION OF ILLINOIS.

WATER-CLOSET.

1,175,523.

Specification of Letters Patent. Patented Mar. 14, 1916.

Application filed April 8, 1913. Serial No. 759,771.

To all whom it may concern:

Be it known that I, ARTHUR M. HOUSER, a citizen of the United States, and residing at Chicago, in the county of Cook and State 5 of Illinois, have invented certain new and useful Improvements in Water-Closets, of which the following is a specification, reference being had to the accompanying drawing.

10 My invention relates generally to new and useful improvements in water closets, and has for its principal objects the provision of improved means whereby a wall closet bowl may be rigidly and adjustably supported on 15 a drainage fitting independently of any positioning of the main soil pipe; and the provision of an adjustable connection between the bowl and the drainage fitting which is adapted to have a tight and yet flexible joint 20 with the bowl outlet and which is further designed to prevent fracture of bowl parts when the bowl is subjected to strain.

These, together with such objects as may hereinafter appear, or are incident to my 25 invention, I attain by means of a construction illustrated in preferred form in the accompanying drawings, wherein:

Figure 1 is a side elevation of the wall closet showing the application of my invention thereto.

Figure 2 represents a plan view of Figure 1.

Figure 3 is an enlarged detail drawing of a portion of Figure 1.

35 Figure 4 is a sectional view on the line III—III of Figure 3.

Figure 5 is a perspective of the yoke.

I am aware that it is old in the art to transmit the thrust of a wall closet bowl 40 through the medium of a collar to the soil pipe, but my invention is designed to provide means which effectually takes this thrust independently of any positioning of the soil pipe, together with an adjustable 45 compression member interposed between the discharge end of the bowl and the soil pipe inlet, and having a flexible connection with the former to insure a tight joint therebetween under the most unfavorable conditions, and which is further designed to pre-

vent fracture of bowl parts when the bowl is subjected to a severe strain.

In disclosing my invention, the numeral 6 indicates the wall closet bowl which is adapted to be positioned against the front 55 face of the partition 7, and is shown provided with a suitable flushing connection as at 8. The bowl 6 has a discharge outlet 9 terminating at a boss 6^a formed on the rear face of the bowl which latter is further provided with the bossed flange 10 adapted to fit around the large opening 7^a in the partition as clearly shown in Figures 1 and 3.

The soil pipe to the rear of the partition 7 is represented by the numeral 11 and interposed is a laterally disposed drainage fitting or L 12, providing an inlet opening 13 leading to the soil pipe 11, and which has an integrally formed socket 14 interiorly threaded to receive the externally threaded 60 rear portion of a nipple 15 whose forward end 15^a is adapted to be in register with the bowl discharge outlet 9.

Surrounding the said discharge outlet, and formed in the boss 6^a in the rear face 65 of the bowl, is an annular recess 16 constituting a seat of sufficient depth to receive therein an annular gasket 17 against which the front end 15^a of the nipple is designed to take in order to obtain a tight and at the 70 same a flexible tongue and groove joint between the nipple and the discharge end of the bowl, as indicated at 17^a in Figure 3.

For the purpose of affording a support to the bowl, I provide a yoke 18 which is 85 screwed onto the lateral socket 14 whose outer periphery is threaded to receive it. The web of the yoke is of sufficient width in cross-section to afford the requisite degree of strength and rigidity, and extends outwardly away from its threaded bore 19 to form the side web portions 20, and depends downwardly and centrally therefrom to terminate below the bore at its lower extremity 21.

95 The bowl is supported from the yoke by what I term a three-point suspension, and to this end the side portions 20 of the yoke have threaded openings at 20^a to receive the threaded ends of the two bolts 22 which ex- 100

tend forwardly at each side of the median line of the nipple, and the lower web portion 21 is likewise provided with a bolt hole 21^a for a similar bolt 23, which together with the bolts 22 extend beyond and through the opening 7^a in the partition to pass loosely through bolt punchings provided in the bowl flange 10.

When in position against the partition 7, 10 the flange of the bowl surrounds and encloses the opening 7^a, with the threaded forward ends of the bolts projecting through the bolt punchings. Nuts 22^a and 22^b are carried on the threaded forward ends of the 15 bolts 22, adapted to bear respectively against the front and rear faces of the bowl flange 10, and similarly the bolt 23 is provided with the nuts 23^a and 23^b.

Accurate and true positioning of the bowl 20 with respect to the partition is easily attained through the range of adjustability afforded by these nuts on their respective bolts, any tendency of the latter to turn in the yoke being prevented by the lock nuts 24. With the parts now assembled in this 25 position, the nipple may be turned in the socket to advance it centrally under compression against the gasket 17 to obtain the desired tongue and groove connection and thereby insure a tight and yet flexible joint. When the parts are thus brought into their 30 desired position the lock nut 25 is tightened to lock the yoke and nipple in position and to compress the packing 26 thereby obtaining a tight joint between the nipple 15 and the lateral inlet of the drainage fitting.

From the foregoing it will be apparent that inasmuch as the bolts 22 are under tension and the bolt 23 is under compression, 10 the thrust on the latter is translated directly to the yoke which is arched forwardly at 18^a and provided with the integrally formed ribs 18^b to better take the thrust from the bowl. The flexible compression joint between the nipple and the rear face of the 15 bowl effectually prevents fracture of the bowl proper when the latter is subjected to a severe strain, and is designed to insure a tight joint under the most unfavorable conditions.

It will be noted on an inspection of the drawings, particularly Figure 3, that I provide supporting means of simple character, all readily accessible and adjustable, and 20 which after correct adjustment connect the bowl rigid to the drainage L, thereby effectually preventing movement of the bowl in any manner. Other advantages will be perceived by those skilled in the art.

Having thus described my invention, and 25 illustrated its use what I claim as new and desire to secure by Letters Patent is the following:—

1. In combination, a bowl having a dis-

charge outlet in its rear face, a laterally disposed L forming the discharge inlet leading to the drainage piping, a supporting member carried at the rear of a partition and arching forwardly toward the bowl, a connection between the outlet and the inlet, and connections between the supporting member and the bowl comprising tension and compression members provided with means adapted to adjust the position of the bowl, the thrust of the bowl being wholly taken by the said arched supporting member, substantially as described.

2. In combination, a bowl provided with an outlet opening, piping including a laterally disposed L having an inlet opening, a connection extending between the outlet and the inlet openings and capable of adjustment therebetween, means to support the bowl from the piping including an adjustable supporting member mounted on the laterally disposed L, and a locking member carried by the said connection whereby it is locked when in adjusted position.

3. In combination, a bowl having an outlet in its rear face, a laterally disposed inlet pipe leading to the drainage line, and provided with a threaded socket portion, a connection between the bowl outlet and the inlet pipe including a short pipe section having one end adjustably received in the inlet pipe and capable of being caused to advance toward the bowl to obtain a tight joint therewith, means whereby the bowl is wholly supported from the lateral inlet pipe comprising a flanged yoke screwed on the said threaded socket and tension members between the yoke and the bowl, with a compression member adapted to transmit the thrust of the bowl to the yoke, the latter being forwardly arched to better take the thrust.

4. In combination, a closet bowl having an outlet and an annular seat formed about said outlet, a flexible gasket disposed in said seat, an inlet pipe in line with said outlet, a tubular connection adjustably carried at one end in the inlet pipe and capable of being axially advanced therein to have its peripheral free edge portion centrally engage with the gasket to provide a tight and compression joint about the outlet, and bowl supporting means for relieving the said joint of bowl thrust.

5. In combination, a bowl having an outlet, an inlet pipe, a connection between the outlet and the inlet pipe, bowl supporting means on the inlet pipe adapted to relieve said connection of thrust from the bowl and arching forwardly toward the bowl to better take the thrust, and connections between the said means and the bowl, substantially as described.

6. In combination, a bowl having an out-

let, an inlet pipe, a bowl supporting member movably mounted on said inlet pipe, a nipple connection between said outlet and said inlet pipe, and a locking means on said

signed my name in the presence of the two
subscribed witnesses.

ARTHUR M. HOUSER.

6 nipple adapted to lock the supporting member, substantially as described.

In testimony whereof I have hereunto
